(57) CLAIM

The ornamental design for a lipstick case as shown and described.

DESCRIPTION

FIG. 1 is a front, right, top perspective view of a lipstick case showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front, right, top perspective view thereof with the cap removed.

FIG. 9 is a front elevation view thereof with the cap removed.

FIG. 10 is a left side elevation view thereof with the cap removed.

FIG. 11 is a right side elevation view thereof with the cap removed.

FIG. 12 is a top plan view thereof of the main body of the lipstick case, shown separately without the cap to reveal aspects of the design that may not be apparent in other views; and,

FIG. 13 is a bottom plan view thereof of the main body of the lipstick case, shown separately without the cap.

1 Claim, 8 Drawing Sheets
